UNITED STATES PATENT OFFICE.

FRED M. LOCKE, OF VICTOR, NEW YORK.

INSULATOR.

No. 822,211.

Specification of Letters Patent.

Patented May 29, 1906.

Application filed June 23, 1902. Serial No. 112,933.

To all whom it may concern:

Be it known that I, FRED M. LOCKE, of Victor, in the county of Ontario, in the State of New York, have invented new and useful 5 Improvements in Insulators, of which the following, taken in connection with the accompanying drawings, is a full, clear, and exact description.

This invention relates to improvements in 10 insulators constructed of porcelain, earthenware, glass, or similar material.

My object is to construct an insulator in such a way as to increase the arcing distance and insulating area between the 15 conducting-wire and the pin, thereby preventing the arcing of the current and burning of the pin.

To that end my invention consists in constructing the center piece of the insulator 20 with a broad skirt tapering upwardly as it approaches the top portion of the insulator, thereby forming a center piece which is bell shape, the center being provided with the usual opening for the pin; and to that end 25 my invention further consists in the several new and novel features of construction, which are hereinafter described, and specifically set forth in the claim hereunto annexed. It is constructed as follows, reference being had 30 to the accompanying drawing, in which I show a vertical section of the insulator complete.

a is the top portion constructed in the ordinary manner, having recesses *a'*, which is 35 adapted to receive the upper end of the center piece *b*. The center piece at its upper end is of any shape desired; but as it approaches the lower end it extends outwardly, as shown, thereby imparting to the center 40 piece the bell-shaped appearance, and has the effect of increasing the insulating area

upon the face of the center piece and at the same time increasing the arcing distance between the conducting-wire and the pin, thereby preventing the arcing of the current to 45 this point.

c is the center pin, opening in the base of the center piece, and by flaring the base of the center piece downwardly and outwardly the walls of the opening *c* are gradually increased in thickness, and therefore the current is less liable to leak or arc to the pin which is inserted in the opening *c*, which arcing or leakage might tend to burn the pin off. As a further protection against the accumulation of moisture at the base of the insulator the top *a* is made in the form of an inverted cup and is fitted over and upon the upper end of the part *b*, which enters the recess *a'*. This top *a* is nearly the same diameter of the part *b*, and its upper face is convex, so as to deflect any moisture beyond the thickened base of the center piece *b* where it is joined onto the pin and cross-arm. 55

Having described my invention, what I 60 claim, and desire to secure by Letters Patent, is—

A bell-shape porcelain center piece gradually increasing in diameter from top to bottom and having a central threaded aperture 70 extending upwardly from its lower face, the upper end of said center piece being substantially flat and parallel with its lower end face, and a porcelain cap resting upon the flat upper end of the center piece. 75

In witness whereof I have hereunto set my hand on this 9th day of June, 1902.

FRED M. LOCKE.
